(57) **CLAIM**

The ornamental design for a wrist phone, as shown and described.

DESCRIPTION

FIG. 1 is a front elevational view of the wrist phone of the present invention;

FIG. 2 is a rear elevational view of the wrist phone of FIG. 1;

FIG. 3 is a left side elevational view of the wrist phone of FIG. 1;

FIG. 4 is a right side elevational view of the wrist phone of FIG. 1;

FIG. 5 is a top plan view of the wrist phone of FIG. 1; and,

FIG. 6 is a bottom plan view of the wrist phone of FIG. 1. The broken lines showing of numbers in FIGS. 1 and 5 are for illustrative purposes only and form no part of the claimed design.

1 Claim, 6 Drawing SheetsFIG. 1

FIG. 3

FIG. 4
